UNITED STATES PATENT OFFICE.

WALTER I. TUTTLE, OF PROVIDENCE, RHODE ISLAND, ASSIGNOR TO FRANK MOSSBERG COMPANY, OF ATTLEBORO, MASSACHUSETTS, A CORPORATION OF RHODE ISLAND.

BEAM CONSTRUCTION.

1,375,644.

Specification of Letters Patent. Patented Apr. 19, 1921.

Application filed August 10, 1918. Serial No. 249,227.

To all whom it may concern:

Be it known that I, WALTER I. TUTTLE, a citizen of the United States, and a resident of Providence, in the county of Providence and State of Rhode Island, have invented an Improvement in Beam Construction, of which the following is a specification.

This invention relates to beam construction. One of the objects thereof is to provide a simple and practical construction of beams possessing strength and durability in a high degree. Another object is to provide a beam head construction which shall be light and yet well adapted to meet the hardest conditions of practical use. Another object is to provide a loom beam head construction in which the several parts may be individually replaced. Other objects will be in part obvious and in part pointed out hereinafter.

The invention accordingly consists in the features of construction, combinations of elements and arrangement of parts which will be exemplified in the structure hereinabove described and the scope of the application of which will be indicated in the following claims.

In the accompanying drawings in which is shown one or more of various possible embodiments of this invention,

Figure 1 is an end view partially broken away in order to show the construction more clearly; and

Fig. 2 is a section taken substantially on the line 2—2 of Fig. 1.

Similar reference characters refer to similar parts throughout both views of the drawings.

Referring now to Fig. 2 of the drawings there is shown a head member 10 preferably pressed out of sheet steel and provided with the desired flange 11 at its outer edge to stiffen this part. This member 10 is fitted about a shoulder 12 on a heavy collar 13 which in turn is mounted upon the shaft 14. The head is held securely against the end of the barrel 15 by any suitable detachable means not here shown as such means forms in itself no part of the present invention. The adjacent surface of the head member is preferably provided with an annular recess within which the end of the cylindrical barrel fits, as shown at 15a.

Also mounted upon the shoulder 12 is a pulley 16 preferably stamped out of sheet 55 steel which extends outwardly with the head member 10, resting against the same, and thence in a direction parallel to the barrel to form the pulley face 17. This pulley terminates in a flange 18 which serves the double purpose of stiffening the edge and holding the belt thereon in place.

A series of rivets 19 pass through the flange 20 of the collar 13 and through both the members 16 and 10 as shown in Fig. 2 65 of the drawings, thus securely holding these parts together. Furthermore, the pulley 16 and head member 10 are additionally held together at points farther outward in a radial direction by rivets, as at 21, or 70 otherwise.

In considering the action of the device, it is to be noted that the head construction as a whole, while light, is extremely rigid as its inner portions which would be subject to the greatest bending stress are formed of two thicknesses of sheet metal rigidly held together. Furthermore, if these parts should become bent in use, they are readily straightened as distinguished 75 from the result in a cast head member in which a crack not only ruins the head but often the yarn wound on the beam. If for any reason one of the parts becomes injured beyond repair, it may be separated 80 from the remaining parts by suitable tools and replaced. This action can be followed moreover if it is desired to substitute a head or pulley of larger or smaller size. The entire head construction is readily adaptable 85 to replace the heads of beams of the ordinary construction as it requires no special co-acting parts.

It is to be understood that the term "pulley" is used broadly throughout to comprehend either a member which may be employed for driving purposes or as is commonly the case in loom beam construction, for retarding purposes, by having a frictional member wrapped about the same.

It will thus be seen that there is provided a construction in which the several objects of this invention are achieved.

As various possible embodiments might be made of the above invention and as various changes might be made in the em-

bodiment above set forth, it is to be understood that all matter herein set forth or shown in the accompanying drawings is to be interpreted as illustrative and not in a 5 limiting sense.

I claim as my invention:

1. In beam construction, in combination, a barrel, a beam head, a pulley member provided with an inwardly extending flange 10 secured to the inner portions of said beam head, a shaft, and means mounted upon said shaft and engaging said flange to hold said head against the end of said barrel.
2. In beam construction, in combination, 15 a sheet metal head provided with a central opening, and a sheet metal pulley member having an inwardly extending continuous flange resting against the inner portions of said head substantially down to said opening and secured thereto whereby the inner portions of said head are reinforced by the flange of said pulley.
3. In beam construction, in combination, 25 a barrel, a beam head, a shaft through said barrel, a pulley member provided with a portion shaped to rest against and be secured to said head, and means mounted upon said shaft and holding said head against the end of said pulley member.
4. In beam construction, in combination, 30 a supporting collar provided with a shoulder directed toward the barrel of the beam, and a sheet metal pulley member having at its side away from the beam an outwardly 35 directed flange and at its side toward the beam an inwardly directed flange fitted

about said shoulder and secured to said collar.

5. In beam construction, in combination, 40 a supporting collar, and a pair of sheet metal members secured thereto one of which forms the head of the beam and the other of which is shaped to form a pulley member, said sheet metal members resting against one another at their inner portions 45 to form a head of added thickness with respect to the outer portions thereof.

6. In beam construction, in combination, 50 a supporting collar, and a pair of sheet metal members, one of which forms the head of the beam and the other of which is shaped to form a pulley member secured thereto, said sheet metal members resting against one another at their inner portions 55 to form a head of added thickness with respect to the outer portions thereof and said collar being provided with a shoulder about which said sheet metal members are fitted.

7. In beam construction, in combination, 60 a pair of sheet metal head members having their inner portions resting one against the other, and secured one to the other at spaced intervals, one of said members extending outwardly to complete a head and the other extending laterally therefrom to form a 65 pulley member, a shaft, and means on said shaft holding said head members against the end of said barrel.

In testimony whereof, I have signed my name to this specification this 29th day of 70 July, 1918.

WALTER I. TUTTLE.
